United States Patent [19]

Weber et al.

[11] Patent Number: Des. 314,176

[45] Date of Patent: ** Jan. 29, 1991

[54] FIBER OPTIC COMPONENT

[75] Inventors: Jocelyn M. Weber, Palo Alto; Douglas M. Thom, Woodside; Michael T. Kennedy, Mountain View, all of Calif.

[73] Assignee: Hewlett-Packard Company, Palo Alto, Calif.

[**] Term: 14 Years

[21] Appl. No.: 103,576

[22] Filed: Sep. 30, 1987

[52] U.S. Cl. D13/133; D13/199

[58] Field of Search D13/133; D16/130; 350/96.2; 439/314-319

[57] CLAIM

The ornamental design for a fiber optic component, as shown and described.

DESCRIPTION

FIG. 1 is a perspective view of a fiber optic component showing our new design on an enlarged scale;

FIG. 2 is a front elevational view of a fiber optic component showing our new design;

FIG. 3 is a top plan view thereof;

FIG. 4 is a rear elevational view thereof;

FIG. 5 is a bottom plan view thereof;

FIG. 6 is a left side elevational view thereof; and

FIG. 7 is a right side elevational view thereof.

FIG 1

FIG 2

FIG 4

FIG 3

FIG 5

FIG 6

FIG 7
